US00D836389S

(12) **United States Design Patent** (10) **Patent No.:** **US D836,389 S**
(45) **Date of Patent:** **** Dec. 25, 2018**

(54) **CONTAINER LID**

(71) Applicant: **YETI Coolers, LLC**, Austin, TX (US)

CN 103538798 A 1/2014
CN 303894653 10/2016

(72) Inventors: **Edward Abante**, Austin, TX (US);
Steve Charles Nichols, Austin, TX (US)

(Continued)

(73) Assignee: **YETI Coolers, LLC**, Austin, TX (US)

(**) Term: **15 Years**

(21) Appl. No.: **29/598,614**

(22) Filed: **Mar. 27, 2017**

(51) **LOC (11) Cl.** **07-99**

(52) **U.S. Cl.**

USPC **D7/392.1**

(58) **Field of Classification Search**

(57) **CLAIM**

The ornamental design for a container lid, as shown and described.

DESCRIPTION

FIG. 1 is a front perspective view of a container lid showing our new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is an exploded view thereof.

The broken lines immediately adjacent to the shaded area represent unclaimed boundaries of the design. The broken lines showing the remainder of the container lid depict portions of the article that form no part of the claimed design.

1 Claim, 5 Drawing Sheets
